UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILE.

Application filed July 24, 1920. Serial No. 398,628.

To all whom it may concern:

Be it known that I, JOHN T. QUIGLEY, a citizen of the United States, and a resident of Boston, in the county of Suffolk and State of Massachusetts, have invented an Improvement in Files, of which the following description, in connection with the accompanying drawings, is a specification, like characters on the drawings representing like parts.

This invention relates to files of the class in which the sheets are arranged with their identification-receiving margins in overlapping relationship, and aims to improve the means for mounting the sheets to facilitate removal, replacement and reclassification of the latter, and to ensure accurate spacing and alignment of the sheets.

My invention will be best understood by reference to the following description, when taken in connection with the accompanying drawings of one specific embodiment thereof, while its scope will be more particularly pointed out in the appended claims.

In the drawings:

Fig. 1 is a front elevation of a file exemplifying my invention, showing all of the sheets in an upstanding position;

Fig. 2 is an elevation similar to Fig. 1, but showing the lowermost sheet unfolded to expose its carrier;

Fig. 3 is a sectional view on line 3—3 of Fig. 1;

Fig. 4 is a sectional view on line 4—4 of Fig. 1; and

Fig. 5 is a perspective view of one of the sheet carriers on an enlarged scale.

Referring to the drawings, and to the embodiment of my invention which I have selected for exemplification, I have shown a file comprising a series of sheets 10 arranged with their identification-receiving margins in overlapping relationship. In the example shown, each sheet is folded and presents two leaves. Although this is not essential, it is preferred, first, because the capacity of each sheet is thereby increased, and, second, because of the greater convenience of attachment of the sheets to the sheet carriers presently to be described. In the construction shown, each sheet is folded precisely midway between its top and bottom edges, along the folding line B—B shown in Fig. 2, and the sheet is provided with a considerable number of perforations 11, herein two, each

of which is intersected by the folding line B—B.

Associated with each sheet is a sheet carrier designated generally by the numeral 12 (see Fig. 5), having two parts 13 and 14 between which is a guide 15 for all the carriers. In the present embodiment, the part 13 is in the form of a bar of suitable sheet material, preferably metal, bent to form a base 16, and two projecting lugs 17 received in the perforations 11, respectively, and provided with openings 18, in which the part 14 is received. The latter is preferably in the form of a bar which may be a round wire, and this wire is preferably resilient, although this is not at all essential. The wire 14 is received within the fold of the sheet, while the base 16 of the bar 13 is without the fold, and the lugs 17 project through the perforations 11 to the inside of the fold, where they present openings 18 for the convenient introduction and removal of the wire (see Fig. 2) by a lengthwise sliding motion of the latter along the folding line B—B. The introduction of the wire is facilitated by bending the ends of the lugs 17, as at 19, parallel with the base 16, and by making the openings 18 in the form of elongated slots which are presented partly in the upstanding portions of the lugs and partly in the laterally bent ends of the latter. In the case of a folding sheet such as herein exemplified, the vertical dimension of its perforations 11 (that is to say, in a direction perpendicular to its identification-receiving margins) is approximately equal to twice the width of the bar 13, so that when the sheet is folded, as represented at the bottom of Fig. 1, each perforation then presents in effect a perforation whose height is approximately equal to the width of the bar. Sufficient clearance is provided to permit the lugs to be introduced into and withdrawn from the perforations with ease, and to permit turning of the sheet about the wire as a pivot, without interference between the edges of the perforations and the lugs. The sheets may be presented in an upstanding or a depending position, and may be turned to and fro from one of these positions to the other, and, moreover, each may be unfolded to expose the inner surface. Thus each sheet presents four pages, any one of which is instantly available for purposes of recording and inspection.

It will be remembered that the guide 15, which is conveniently in the form of a thin sheet metal bar, is interposed between the wire 14 and the base 16 of the bar 13. The lugs 17 are spaced apart a distance very slightly greater than the width of the guide 15, which is received between said lugs. It follows that the sheet carriers with their attached sheets can be moved up and down the guide 15 by a sliding motion along the latter. Any sheet may be conveniently removed from its place by unfolding the same to expose its wire, which is then withdrawn, thus freeing the sheet and allowing the latter to be removed from the lugs. The sheet and its carrier may be reinserted in the same place, or at another point, by simply sliding the sheet carriers and sheets along the guide, and making a space at the desired point, whereby the bar is placed behind the guide and brought forward until its lugs project forward from the front of the guide. The sheet may now be placed upon the lugs with the latter received in the perforations in the sheet, and finally the wire may be inserted in its place and the sheet then folded.

If a sheet carrier from which a sheet has been removed in the manner above described, 30 be left in its place, the absence of such sheet will be indicated by the exposure of twice the normal amount of the identification receiving margin of the next adjacent sheet. If it is desired that this indication should 35 remain for some time, the wire of such carrier should be reinserted in its bar immediately after the sheet is removed therefrom.

The operation of removing a given sheet from its carrier and replacing the same 40 thereon is facilitated by the provision of a back plate in the form of a panel 20, which I prefer to employ in association with the guide 15. This plate presents an abutment against which the bases 16 of the bars 13 45 may rest. Preferably, the guide 15 is so related to the back plate as to be movable toward and from the latter. One convenient way of accomplishing this is to make the guide of thin and preferably resilient sheet metal, having its terminal portions suitably attached to the plate 20 as by a screw 21 at the top and rivets 22 at the bottom. In the present example, the upper edge of the plate 20 (see Fig. 4) is rolled 50 about a rod 23, which may provide a convenient means for supporting the panel, and the screw 21 may be threaded into this rod, while the lower edge of the plate may be bent upon itself to present a front wall 55 24 and a pocket 25 behind the latter. The lower end of the guide 15 is extended into this pocket, and is bent at or about a bar 26 also received in the pocket. The rivets 22 extend through the several thicknesses 60 of metal thus presented, and firmly secure

them together. The pocket 25 may present a convenient holder for a label which may be viewed through an aperture 27 best shown at the bottom of Fig. 1, this label-holder, however, having nothing to do with my present invention. Reverting for a moment to the upper end of the guide 15, the latter is wrapped part way about the rod 23, and the upper edge of the plate 20, as clearly shown in the upper portion of Fig. 75 4, and I prefer to employ a sheet metal clip 28, which, in turn, is wrapped about the terminal portion of the guide 15, and assists in holding the latter in place, said clip being perforated to receive the screw 21. 80

The back plate or panel 20 may, and does herein, perform another important function,—that of presenting guides for the lateral edges of the sheets. This is desirable in case the guide 15 is relatively narrower as compared with the width of the sheets, as in the present example, in which case, the panel is provided with a pair of forwardly projecting flanges 29, best shown in Fig. 3, between which and the edges of 85 the sheets just sufficient clearance is allowed to cause the guides to maintain the alignment of the sheets while still permitting them to slide freely up and down, and to turn about their hinges. 95

The operation of the file should be apparent without further description, except to add that since the guide 15 is flexible, it may be pressed toward the back plate 20 during the attachment of a sheet to its carrier, thus permitting the sheet to be pressed backward correspondingly to facilitate the introduction of the wire through the openings in the lugs. When the sheet is released, the guide will spring forward 105 to its normal position. The flexibility of the guide is advantageous for the further reason that it facilitates removal and replacement of the bars. Preferably, the height of the lugs 17 is somewhat greater 110 than the normal distance between the guide and the back plate. This distance, however, may be increased at will by simply springing the guide forward a sufficient amount to allow the lugs to pass between 115 the guide and the back plate.

Having thus described one embodiment of my invention, but without limiting myself thereto, what I claim and desire by Letters Patent to secure is:

1. In a file, the combination of a series of overlapping sheets provided with perforations, a series of sheet-carriers maintaining the minimum overlap of said sheets, each sheet-carrier comprising two parts, 125 one extending through said perforations and secured to the other at two points, and a support for said sheet-carriers extending between the two parts of each intermediate said perforations. 130

2. In a file, the combination of a series of overlapping sheets provided with perforations, a series of sheet-carriers maintaining the minimum overlap of said sheets, each sheet-carrier comprising two parts, one provided with projections extending through said perforations and secured to the other at two points, and a support for said sheet-carriers, extending between the two parts of each intermediate said projections. 10
3. In a file, the combination of a series of overlapping sheets provided with perforations, a series of sheet-carriers, maintaining the minimum overlap of said sheets, each sheet-carrier comprising two parts, one having projections extending through said perforations and provided with openings, and the other extending through said openings, and a support for said sheet-carriers, ex- 15
- tending between the two parts of each intermediate said openings. 20
4. In a file, the combination of a series of overlapping sheets provided with perforations, a series of sheet-carriers maintaining the minimum overlap of said sheets, each sheet-carrier comprising two parts, one having projections extending through said perforations and provided with openings, and the other extending through said openings, a support for said sheet-carriers, presenting a part extending between the two parts of each sheet-carrier intermediate said openings, and means to prevent accidental escape of the one part of each said sheet-carrier from the openings of the other. 30 35

In testimony whereof, I have signed my name to this specification.

JOHN T. QUIGLEY.
